ABSTRACT OF THE DISCLOSURE

A detergent composition incorporates from 1 to 60% by weight of a water-soluble or water-dispersible salt of a heterocyclic dicarboxylic acid having the general formula:

wherein R can be hydrogen or a substituent such as bromine, chlorine, hydroxy, carboxy, C_{1-4} alkyl, amino or alkyl-substituted amino. The salt acts as a detergency builder, and may act also as an inhibitor for the decomposition, caused by heavy-metal catalysis, of any peroxy-compounds such as perborates, in the detergent composition.

The present invention relates to detergent compositions, and in particular to fabric-washing detergent compositions, incorporating detergency builders.

At the present time there is considerable pressure being brought to bear on the manufacturers of detergent compositions to reduce the amount of phosphorus-containing compounds in such compositions. This situation has arisen because of the suggestion that the use of phosphorus-containing compounds in detergent compositions is a factor contributory to the phenomenon of eutrophication. Such phosphorus-containing compounds are generally present in detergent compositions as detergency builders. For many years the most commonly employed detergency builder has been sodium tripolyphosphate, and it is this compound in particular that is being blamed for the contribution of detergent compositions to the problems of eutrophication. It is common for detergent compositions to contain from 30 to 50% by weight of sodium tripolyphosphate. Sodium tripolyphosphate is a very efficient detergency builder and can also be manufactured cheaply.

Hence at the present time there is a need for a substitute for sodium tripolyphosphate that can be used to produce detergent compositions that clean efficiently and yet which will not interfere adversely with man's environment.

By the invention it has been found that the detergency of a detergent composition can be built effectively using a water-soluble or water-dispersible salt of a chemical compound having the general formula:

(I)

wherein R is a hydrogen atom, a chlorine atom, a bromine atom, a hydroxyl group, an amino group, an alkyl-substituted amino group, a carboxyl group, or an alkyl group containing from 1 to 4 carbon atoms.

Hereinafter, a water-soluble or water-dispersible salt

2

of a chemical compound of Formula I is referred to as a heterocyclic dicarboxylic acid salt. These heterocyclic dicarboxylic acid salts are known compounds.

The invention provides a detergent composition comprising a detergent-active compound and from about 1 to about 60% by weight of a heterocyclic dicarboxylic acid salt.

Preferably, the heterocyclic dicarboxylic acid salt comprises from about 5 to about 60%, and particularly preferably from about 15 to about 55%, by weight of the detergent composition.

Where R is an alkyl-substituted amino group, the preferred groups are N-methyl amino, N-ethyl amino, N,N-dimethyl amino and N,N-diethyl amino groups.

Where R is an alkyl group, methyl, ethyl and n-propyl groups are preferred.

It is preferred that R is a hydrogen atom, a hydroxyl group, an amino group, an alkyl-substituted amino-group, a carboxyl group or a methyl group.

It is particularly preferred that R is a hydrogen atom or a hydroxyl group.

The heterocyclic dicarboxylic acid salt is preferably an alkali-metal salt, particularly a sodium salt, although potassium and lithium salts can be used. If desired, the heterocyclic dicarboxylic acid salt may be an ammonium or substituted ammonium salt.

It will be appreciated by those skilled in the art that the detergency building benefits of a heterocyclic dicarboxylic acid salt of the invention may still be obtained if a detergent composition incorporates the corresponding free heterocyclic dicarboxylic acid, or the heterocyclic dicarboxylic acid in a partially neutralised form, complete neutralisation of the heterocyclic dicarboxylic acid taking place when the detergent composition is dissolved in water.

The heterocyclic dicarboxylic acid of Formula I above wherein R is a hydrogen atom is pyridine-2,6-dicarboxylic acid, which is known also as dipicolinic acid.

Many conventional fabric-washing detergent compositions incorporate peroxy-compounds, such as sodium perborate, as oxygen-releasing bleaching agents. Water in which such detergent compositions are dissolved often contains minor traces of catalysts, such as heavy metal ions, which cause unwanted decomposition of the peroxy-compounds to take place and hence cause a drop in the bleaching efficiency of the detergent compositions. It has been found, as an added advantage of the detergent compositions of the invention, that the heterocyclic dicarboxylic acid salts of the invention can act as inhibitors for this decomposition. The preferred peroxy-compounds are sodium perborate and sodium percarbonate, and if desired may be present in a detergent composition in an amount of from about 1 to about 30% by weight of the detergent composition.

A detergent composition of the invention will contain at least one detergent-active compound. Generally, the detergent-active content of the detergent composition will be from about 1 to about 50%, preferably from about 5 to 35%, and particularly preferably from about 10 to

about 25%, by weight of the composition. The nature of the detergent-active compound or compounds in the detergent composition is not an essential feature of the invention: any of the detergent-active compounds conventionally incorporated in or proposed for use in detergent compositions may be used, and those skilled in the art of formulating detergent compositions will be familiar with these detergent-active compounds and the various amounts and combinations in which they may advantageously be used. The detergent-active compound or compounds may be anionic, nonionic, amphoteric or zwitterionic in character.

70

Typical anionic detergent-active compounds are water-soluble or water-dispersible salts of various organic acids. The cations of such salts are generally alkali-metals, such as sodium and, less preferably, potassium, but other cations, such as ammonium and substituted ammonium, can be used if desired. Examples of suitable organic acids are: alkyl benzene sulphonic acids, the alkyl chains of which contain from about 8 to about 20 carbon atoms, such as p-dodecyl benzene sulphonic acid and linear alkyl (C_{10-15}) benzene sulphonic acid; the mixtures of sulphonic acids obtained by reacting linear and branched olefins, particularly linear "cracked-wax" or "Ziegler" alpha-olefins, containing from about 8 to about 22 carbon atoms, with sulphur trioxide; alkyl sulphonic acids obtained by reacting alkanes containing from about 8 to about 22 carbon atoms with sulphur dioxide/oxygen or sulphur dioxide/chlorine (followed by hydrolysis in the latter case), or by the addition of bisulphite to olefins, particularly linear "cracked-wax" or "Ziegler" alpha-olefins, containing from about 8 to about 22 carbon atoms; alkyl sulphuric acids obtained by reacting aliphatic alcohols containing from about 8 to about 22 carbon atoms with sulphur trioxide; alkyl ether sulphuric acids, obtained by reacting molar quantities of aliphatic alcohols containing from about 6 to about 18 carbon atoms with from about 1 to about 15 moles of ethylene oxide, or a suitable mixture of ethylene oxide and propylene oxide, and subsequently reacting the alkoxylated alcohol with sulphur trioxide to yield the required acid; and natural or synthetic aliphatic carboxylic acids, particularly those derived from natural sources such as tallow, coconut oil, palm oil, palm kernel oil and groundnut oil.

Examples of suitable nonionic detergent-active compounds are: condensates of alkyl-phenols having an alkyl group (derived, for example, from polymerised propylene, diisobutylene, octene, dodecene or nonene) containing from about 6 to 12 carbon atoms in either a straight chain or branched chain configuration, with about 5 to 25 moles of ethylene oxide per mole of alkyl-phenol; condensates containing from about 40% to about 80% polyoxyethylene by weight and having a molecular weight of from about 5,000 to about 11,000 resulting from the reaction of ethylene oxide with the reaction product of ethylenediamine and excess propylene oxide; condensates of linear or branched-chain aliphatic alcohols containing from 8 to 18 carbon atoms with ethylene oxide, e.g. a coconut alcohol-ethylene oxide condensate containing about 6 to 30 moles of ethylene oxide per mole of coconut alcohol; long-chain tertiary amine oxides corresponding to the general formula $R_1R_2R_3N \rightarrow O$, wherein R_1 is an alkyl radical containing from about 8 to 18 carbon atoms and R_2 and R_3 are each methyl, ethyl or hydroxy ethyl radicals, such as dimethyldodecylamine oxide, dimethyl-octylamine oxide, dimethylhexadecylamine oxide and N-bis (hydroxyethyl) dodecylamine oxide; long-chain tertiary phosphine oxides corresponding to the general formula $RR'R''P \rightarrow O$, wherein R is an alkyl, alkenyl or monohydroxyalkyl radical containing from 10 to 18 carbon atoms and R' and R'' are each alkyl or monohydroxyalkyl groups containing from 1 to 3 carbon atoms, such as dimethyldodecylphosphine oxide, dimethyltetradecylphosphine oxide, ethylmethyltetradecylphosphine oxide, dimethylstearylphosphine oxide, ethylpropylcetylphosphine oxide, diethyldodecylphosphine oxide, bis(hydroxymethyl)dodecylphosphine oxide, bis(2-hydroxyethyl)dodecylphosphine oxide, 2-hydroxypropylmethyltetradecylphosphine oxide, dimethyloleylphosphine oxide and dimethyl-2-hydroxydodecylphosphine oxide; and di-alkyl sulphoxides corresponding to the general formula $RR'S \rightarrow O$, wherein R is an alkyl, alkenyl, beta- or gamma-monohydroxyalkyl radical or an alkyl or beta- or gamma-monohydroxyalkyl radical containing one or two other oxygen atoms in the chain, the R groups containing from 10 to 18 carbon atoms and wherein R' is methyl, ethyl or alkylol radical, such as deodocyl methyl sulphoxide,

5 tetradecyl methyl sulphoxide, 3-hydroxytridecyl methyl sulphoxide, 2-hydroxydodecyl methyl sulphoxide, 3-hydroxy-4-dodecyloxybutyl methyl sulphoxide, 2-hydroxy-3-decyloxypropyl methyl sulphoxide, dodecyl ethyl sulphoxide, 2-hydroxydodecyl ethyl sulphoxide and dodecyl-2-hydroxyethyl sulphoxide.

10 Examples of suitable amphoteric detergent-active compounds are: derivatives of aliphatic secondary and tertiary amines, in which the aliphatic radical may be straight chain or branched and wherein one of the aliphatic substituents contains from about 8 to 18 carbon atoms and one contains an anionic water solubilising group, such as sodium - 3 - dodecylaminopropionate, sodium-3-dodecylaminopropanesulphonate and sodium N-2-hydroxydodecyl-N-methyl-taurate.

15 Examples of suitable zwitterionic detergent-active compounds are: derivatives of aliphatic quaternary ammonium compounds, sulphonium compounds and phosphonium compounds in which the aliphatic radical may be straight chain or branched and wherein one of the aliphatic substituents contains from about 8 to 18 carbon atoms and one contains an anionic water solubilising group, such as 3-(N,N-dimethyl-N-hexadecyl-ammonium) propane-1-sulphonate betaine, 3-(N,N-dimethyl-N-hexadecyl - ammonium)-2-hydroxypropane-1-sulphonate betaine, 3-(dodecylmethyl-sulphonium)propane-1-sulphonate betaine, and 3-(cetyl methylphosphonium)ethane sulphonate betaine.

20 Further examples of suitable detergent-active compounds commonly used in the art are given in "Surface Active Agents, vol. I" by Schwartz and Perry (Interscience 1949) and "Surface Active Agents, vol. II" by Schwartz, Perry and Berch (Interscience 1958), the disclosures of which are included by reference herein.

25 The heterocyclic dicarboxylic acid salts of the invention may comprise the whole of the detergency builder content of a detergent composition of the invention. However, if desired, mixtures of one or more of these heterocyclic dicarboxylic acid salts with one or more known detergency builders may be used. As one of the objects of the invention is to provide an effective detergent composition containing either no phosphorus or at most only a low level of phosphorus, it is preferred that any such other detergency builders should not be phosphorus-containing compounds. Usually the total amount of detergency builders in a detergent composition of the invention will be from about 5 to about 70% by weight of the detergent composition. Many detergency builders are known, and those skilled in the art of formulating fabric-washing detergent compositions will be familiar with these materials. Examples of known detergency builders are sodium tripolyphosphate; sodium orthophosphate; sodium pyrophosphate; sodium trimetaphosphate; sodium ethane-1-hydroxy-1,1-diphosphonate; sodium carbonate; sodium silicate; sodium citrate; sodium oxydiacetate; sodium nitrotriacetate; sodium ethylene-diaminetetraacetate; sodium salts of long-chain dicarboxylic acids, for instance straight chain (C_{10} to C_{20}) succinic acids and malonic acids; sodium salts of alpha-sulphonated long-chain monocarboxylic acids; sodium salts of polycarboxylic acids; i.e. acids derived from the polymerisation or copolymerisation of unsaturated carboxylic acids and unsaturated carboxy acid anhydrides such as maleic acid, acrylic acid, itaconic acid, methacrylic acid, crotonic acid and aconitic acid, and the anhydrides of these acids, and also from the copolymerisation of the above acids and anhydrides with minor amounts of other monomers, such as vinyl chloride, vinyl acetate, methyl methacrylate, methyl acrylate and styrene; and modified starches such as starches oxidised, for example using sodium hypochlorite, in which some anhydroglucose units have been opened to give dicarboxyl units.

30 In addition to the detergent-active compounds and detergency builders, a detergent composition of the invention may contain any of the conventional detergent com-

5

position ingredients in any of the amounts in which such conventional ingredients are usually employed therein. Examples of these additional ingredients are lather boosters, such as coconut monoethanolamide and palm kernel monoethanolamide; lather controllers; inorganic salts such as sodium sulphate and magnesium sulphate; chlorine-releasing bleaching agents such as trichloroisocyanuric acid and sodium and potassium dichloroisocyanurates; antiredeposition agents, such as sodium carboxymethylcellulose; and, usually present only in minor amounts, perfumes, colourants, fluorescers, corrosion inhibitors, germicides and enzymes.

A detergent composition of the invention can be prepared using any of the conventional manufacturing techniques commonly used or proposed for the preparation of detergent compositions, such as slurry-making followed by spray-drying or spray-cooling, and subsequent dry-dosing of sensitive ingredients not suitable for incorporation prior to the drying step. Other conventional techniques, such as nodding, granulation, and mixing by fluidisation in a fluidised bed, may be utilised as and when necessary. Such techniques are familiar to those skilled in the art of detergent composition manufacture.

By using such conventional manufacturing techniques, a detergent composition of the invention may be prepared in any of the common physical forms associated with detergent compositions, such as powders, flakes, granules, noodles, cakes, bars and, in some cases, liquids.

The invention is illustrated by the following examples, in which all parts and percentages are given by weight.

EXAMPLE 1

Two detergent powders having the following formulations were prepared by conventional techniques.

Components:	Parts, percent
Sodium dodecyl benzene sulphonate	18
Detergency builder ¹	50
Alkaline sodium silicate	10
Sodium sulphate	12
Fluorescers, perfumes, antiredeposition agents, water, etc. to	100

¹ Example 1: The disodium salt of pyridine-2,6-dicarboxylic acid.

Comparative Example A: Sodium tripolyphosphate.

The detergencies of these two detergent powders were compared by using them to wash Dacron/cotton test cloths, soiled with an artificial soil, in a Terg-O-Tometer (supplied by U.S. Testing Inc.). The test details were as follows:

Wash cycle:
10 minutes
90 r.p.m.
50° C.
18° H water (Ca:Mg ratio—2:1)
pH 10
Cloth:liquor ratio—1:150
Powder concentration 0.1%

Rinse cycle:
1 minute
37° C.
18° H water (Ca:Mg ratio—2:1)

Each detergent powder was tested twice, and the detergencies were determined from cloth reflectance readings. The following results were obtained:

TABLE I

Powder	Detergency (percent)		
	First test	Second test	Average
Example 1	51.9	56.6	54.3
Comparative Example A	47.3	49.6	48.3

6

These results show that the detergent powder of Example 1 possessed a washing ability superior to that of a conventional detergent powder built with 50% of sodium tripolyphosphate.

EXAMPLE 2

Two detergent powders having the following formulations were prepared by conventional techniques.

Components:	Parts, percent
Sodium dodecyl benzene sulphonate	16
Detergency builder ¹	50
Alkaline sodium silicate	8
Sodium sulphate, fluorescers, perfumes, anti-redeposition agents, water, etc. to	100

¹ Example 2: The disodium salt of pyridine-2,6-dicarboxylic acid.

Comparative Example B: Sodium tripolyphosphate.

When subjected to the test described in Example 1, the detergent powder of Example 2 proved to be superior to the conventional detergent powder of Comparative Example B.

EXAMPLE 3

Two detergent powders were prepared by conventional techniques and having the following essential formulations:

Components:	Parts, percent
Sodium dodecyl benzene sulphonate	20
Anhydrous alkaline sodium silicate (Na ₂ O:SiO ₂ ratio 2:1)	10
Detergency builder ¹	50
Sodium sulphate, water to	100

¹ Example 3: The monohydrate of 4-hydroxy-pyridine-2,6-dicarboxylic acid.

Comparative Example C: Sodium tripolyphosphate.

EXPERIMENT 1

These two detergent powders were used to wash test cloths (pieces of 65/35 polyester/cotton fabric) soiled with an artificial soil composed of vacuum-cleaner dust and free fatty acid. The washes were conducted at various concentrations of the detergent powders in the wash solutions, and were performed in a Terg-O-Tometer (supplied by U.S. Testing Co. Inc.) under the following conditions:

Wash:

10 minutes
50° C.
Water hardness 18° H (Ca:Mg ratio—2:1)
90 r.p.m.
pH 10

Rinse:

1 minute
37° C.
Same water hardness

The detergency efficiency of each detergent powder was calculated using reflectance measurements. The results obtained are given in Table II below:

TABLE II

Detergent powder	Detergency efficiency at concentration of—		
	0.075%	0.1%	0.125%
Example 3	19	28	37
Comparative Example C	13	23	31

These results show that the detergent powder of Example 3 had a greater detergency efficiency than the conventional detergent powder of Comparative Example C.

7
EXPERIMENT 2

The previous experiment was repeated using three higher concentrations. The following results were obtained.

TABLE III

Detergent powder	Detergency efficiency at concentration of—		
	0.15%	0.2%	0.25%
Example 3.....	33	39	39
Comparative Example C.....	30	33	35

The results in Table III confirm the superiority of 15 the detergent powder of Example 3 over that of Comparative Example C.

EXPERIMENT 3

This was the same as Experiment 1, except that the 20 test cloth used was a commercially-available cotton-based test cloth (EMPA 101) supplied by the Swiss Materials Testing and Experimental Institute, Unterstrasse 11, 9001 Saint Gallen, Switzerland.

The following results were obtained.

TABLE IV

Detergent powder	Detergency efficiency at concentration of—		
	0.075%	0.1%	0.125%
Example 3.....	35	43	42
Comparative Example C.....	30	37	41

The results in Table IV also demonstrate the good detergency efficiency of the detergent powder of the invention.

EXPERIMENT

Experiment 2 was repeated at two product concentrations using EMPA 101 test cloths. The results given in Table V below also show the detergency building properties of the detergent powder of the invention.

TABLE V

Detergent powder	Detergency efficiency at concentration of—	
	0.15%	0.2%
Example 3.....	37	40
Comparative Example C.....	42	42

EXPERIMENT 5

Experiment 1 was repeated using a fixed product concentration (0.1%) but with varying degrees of water hardness. The following results were obtained.

TABLE VI

Detergent powder	Detergency efficiency at water hardness of—				
	0° H	4.5° H	9° H	13.5° H	18° H
Example 3.....	59	60	57	58	47
Comparative Example C.....	62	60	56	54	38

The results in Table VI illustrate that the detergency efficiency of the detergent powder of the invention is comparable with that of the conventional detergent powder over a wide range of water hardness.

8

The detergency efficiency figures for the 18° H water are higher than the comparable figures obtained during Experiment 1 because a different batch of the test cloth was used.

EXAMPLE 4

The ability of pyridine-2,6-dicarboxylic acid to act as an inhibitor for the decomposition of peroxy-compounds is illustrated by the following experiment.

Six test solutions were made up as follows, using 30° H (Ca only) water containing 0.5 p.p.m. of cupric ions:

Solution	Percent sodium perborate	Percent pyridine-2,6-dicarboxylic acid
1.....	0.125	0.05
2.....	0.125	0.10
3.....	0.125	0.15
4.....	0.125	0.20
5.....	0.125	0.25

These test solutions corresponded to 0.5% solutions a detergent composition containing 25% by weight of sodium perborate and various levels (from 0 up to 50% by weight) of pyridine-2,6-dicarboxylic acid.

Each test solution was heated from 20° C. up to 95° C. over a period of one hour, and then maintained at 95° C. for a further 10 minutes. Subsequently, the percentage of sodium perborate lost was determined volumetrically using a potassium iodide titration. The following results were obtained.

Solution	Equivalent percent level of pyridine-2,6-dicarboxylic acid in the detergent composition	Percent sodium perborate lost
1.....	0	90.6
2.....	10	6.2
3.....	20	6.2
4.....	30	1.0
5.....	40	1.0
6.....	50	5.1

These results indicate that the heterocyclic dicarboxylic acids of the invention can function as stabilisers for peroxy-compounds in detergent compositions.

What is claimed is:

1. A detergent composition comprising by weight:
  - (a) from about 1 to about 50% of a detergent-active compound selected from the group consisting of anionic, nonionic, amphoteric and zwitterionic detergent-active compounds; and
  - (b) from about 1 to about 60% of a sodium salt of a chemical compound having the general formula:

wherein R is a hydrogen atom or a hydroxyl group.

2. A detergent composition according to claim 1, wherein said sodium salt comprises from about 5 to about 60% by weight of said detergent composition.

3. A detergent composition according to claim 2 which additionally comprises from about 1 to about 30% by weight of a peroxy-compound selected from the group consisting of sodium perborate and sodium percarbonate.

4. A detergent composition comprising by weight:
  - (a) from about 5 to about 35% of a detergent-active compound selected from the group consisting of anionic, nonionic, amphoteric and zwitterionic detergent-active compounds; and,
  - (b) from about 15 to about 55% of the disodium salt of pyridine-2,6-dicarboxylic acids.

5. A detergent composition comprising by weight:
- (a) from about 5 to about 35% of a detergent-active compound selected from the group consisting of anionic, nonionic, zwitterionic and amphoteric detergent-active compounds; and,
  - (b) from about 15 to about 55% of 4-hydroxy-pyridine-2,6-dicarboxylic acid.
